UNITED STATES PATENT OFFICE.

AMBROSIUS BRIECHLE, OF BROOKLYN, NEW YORK, ASSIGNOR TO WALES ADDING MACHINE COMPANY, OF WILKES-BARRE, PENNSYLVANIA, A CORPORATION OF PENNSYLVANIA.

CALCULATING-MACHINE.

1,335,815.

Specification of Letters Patent. Patented Apr. 6, 1920.

Application filed March 20, 1919. Serial No. 283,721.

To all whom it may concern:

Be it known that I, AMBROSIUS BRIECHLE, a citizen of the United States, residing in the borough of Brooklyn, city and State of New York, have invented new and useful Improvements in Calculating-Machines, of which the following is a specification.

More particularly, this invention relates to improved and simplified carriage-controlled machine-actuated counter-selecting means for a multiple counter machine, said means being rendered operative or inoperative at will.

Multiple counter machines at once suggest means to select for operation, one or another set of normally idle counters, or vice versa, to selectively retain one or another set of normally operable counters, out of operative position.

At first, this selection was manually effected by means of a lever, keys, or other devices, pressure on which shifted the desired counter to effective position.

From this beginning, the art developed along two lines. In one, the paper carriage, as it shifted from column to column in tabulating or shuttling operations, effected the necessary adjustment of the parts to select the desired counter on which accumulations were to be made, the other line comprising those devices wherein the operation of the machine itself was relied upon to furnish the power to shift the counter-selecting mechanism in accordance with the desired system or method employed by the operator.

In other words, the art developed carriage-driven counter-selecting mechanisms, and machine-driven counter-selecting mechanisms.

Later, the two lines merged in a type of device embodying a carriage control of machine-actuated counter-selecting mechanism to which my invention relates.

One object of the present invention is to provide a simplified form of automatic carriage-controlled, machine-driven counter-selecting mechanism, which embodies a novel principle of operation, and possesses advantages not found in prior constructions for accomplishing the same result.

Pursuant thereto, I provide the counter-selecting means shown in the pending application of Pentecost and Fisher, filed July 17, 1918, Serial No. 245,273, with transmitting means, adjustable by the carriage in its

travel past the printing point, relatively to a drive means actuated from the main shaft of the machine.

To enable the operator to determine when this drive means shall become active and when it shall remain idle, I have contrived an actuating mechanism operated from the main shaft, and have arranged a manually-controlled coupler, shiftable to connect or disconnect the actuating mechanism and the drive means.

Another object is to utilize the same mechanism by which the carriage controls the selection of counters, to prevent the accumulation of items on any of the sets of counters. In other words, the carriage-controlled counter-selection mechanism which determines the set of counters which shall become effective, also serves as a non-add mechanism.

Heretofore, a separate non-add mechanism has been provided to effect this result.

To these and other ends, my invention includes novel features and combinations of parts, all of which will be more fully set forth hereinafter and particularly pointed out in the claims.

In the accompanying drawings, Figure 1 is a view in side elevation of a multiple counter machine of the well-known Wales type, equipped with one embodiment of my invention, the carriage-controlled, machine-driven counter-selecting mechanism being disconnected, and the machine at rest, with the counter-selecting mechanism in its intermediate position;

Fig. 2 is a similar view, parts being omitted, showing the automatic counter-selecting mechanism coupled for operation, and the parts in action, the main drive shaft having started on its forward stroke, and the counter-selecting mechanism being at one limit of its travel;

Fig. 3 is an enlarged side view, showing the mechanism adjusted to shift the counter-selection member to its intermediate position;

Fig. 4 is a detail rear view, showing the relative positions of the parts; and

Fig. 5 is a detail plan view of the adjustable members on the carriage which position the transmitting mechanism relatively to the driving means, to control the automatic selection of the counters.

110

A multiple-counter calculating machine of the Wales type, is fully set forth in the application of Pentecost and Fisher, filed July 17, 1918, Serial No. 245,273, which 5 may be equipped with an automatic tabulating paper carriage of any suitable design, as that disclosed in the application of Pentecost and Fisher, filed September 28, 1918, Serial No. 256,013, it being understood that 10 the use of the invention is not confined to the Wales machine.

In view of the foregoing disclosures, and the fact that automatic tabulating carriages are old in the art, only sufficient showing of the former construction is included in this application, to enable one skilled in the art to thoroughly understand the present invention.

Calculating and listing machines include 20 a keyboard, comprising a plurality of keys; an accumulating mechanism; a printer mechanism; and a paper carriage.

In the Wales style of machine, as shown for instance, in U. S. patent to Wales 25 797,032, August 15, 1905, to which reference is directed, the numeral keys are arranged in denominational rows and control similarly arranged series of stops located at progressively increasing distances from the forward 30 ends of the denominational racks or positioning bars mounted on their respective front and rear supporting arms, there being one positioning bar to coöperate with each row of stops. Obviously, the location of the 35 particular stop projected by the depression of its numeral key, determines the length of travel of the coacting positioning bar before its arrest by such stop.

For the purposes of this invention, it will 40 be sufficient to indicate the keyboard by the single numeral key 117 (Fig. 1), depression of which projects a stop 115 into the path of a positioning bar 310 pivotally mounted on front and rear supporting arms 312, 311, 45 journaled on a cross shaft 300 and a cross rod 301, respectively.

Restraining links 312^a (Fig. 1) depend 45 from forward extensions 312^m of the front supporting arms 312, and are forked at their lower ends to embrace a restraining and restoring bar 294 extending across the machine and mounted at its opposite ends in the forward ends of rockers 220 journaled at their rear ends on a cross rod 508^a. Springs 383 connected to the respective links 312^a, and to a guide plate 220^b secured to the restraining and restoring bar 294, tend 55 to draw downwardly the links 312^a and rock arms 312 forwardly, to advance the positioning bars, such action being normally resisted by the restraining and restoring bar 294 with which the links contact.

Radius bars 323 (Figs. 1 and 2) journaled on the cross shaft 300 extend into 60 proximity to the free ends of the respective

rockers 220, and carry rolls 340^a entered in and adapted to traverse cam slots 220^m formed in the rockers. A cross rod 303 connects the radius bars to form therewith a swinging frame, and links 214 connect the 70 frame with arms 210^m fixed on the main drive shaft 200.

When the main drive shaft is in its home position, where it is normally held by the usual restoring spring (not shown), the radius bars 323 are held in their rearward positions, shown in Fig. 1, with the rolls 340^a at the rear ends of the cam slots 220^m, to retain the rockers 220 and the restraining bar 294 in their normal elevated positions, 80 and thus hold the positioning bars 310 re-tired against the tension of their drive springs 383.

Turning the main drive shaft 200 forwardly, against the tension of the restoring 85 spring, advances the links 214 and radius bars 323, and causes the rolls 340^a to traverse the cam slots 220^m to depress the rockers 220. Depression of the rockers lowers the restraining and restoring bar 294 90 and further tensions the drive springs 383, to advance the positioning bars 310, through restraining links 312^a and arms 312, until the projected stops 115 arrest the positioning bars. Detents 221 overlying the respective denominational groups of stops 115, and 95 displaceable by the stops when projected, arrest the positioning bars in those denominations wherein no keys 117 have been depressed.

Segmental racks 410, whose stocks 410^m are journaled on a cross rod 401, each have a pin and slot connection 450 with their respective denominational positioning bars 310 to travel therewith.

In the present exemplification of my invention, two series of counters, indicated at 490, 490^a are shown, each of which includes a plurality of denominational arranged 105 numeral wheels equipped with pinions 435, 110 and journaled for independent rotation on their respective axles 400.

In the Wales machine, the opposite ends of the axles 400 carrying the numeral wheels and their pinions 435, are supported so that 115 the pinions 435 are normally out of contact with their coöperating racks 410, by a disengaging means, not herein shown, the disengaging means adapted to be tripped by the rod 303 connecting the swinging radius 120 bars 323, to permit the numeral wheels and pinions to drop into engagement with the racks 410 in an adding operation, at the end of the forward stroke of the main drive shaft, after the racks have advanced to their 125 predetermined positions.

The main drive shaft, on its return stroke, swings the advanced radius bars 323 rearwardly, to cause their rolls 340^a to retrace their paths in the cam slots 220^m and there- 130.

5 by raise the rockers 220, and the restraining and restoring bar 294 carried thereby. The rockers, on such upward thrust, press the restraining and restoring bar against the lowered ends of the restraining links 312^a to swing the front arms 312 rearwardly and retire the advanced positioning bars 310 and racks 410.

10 The racks, during their retirement, turn the active set of numeral wheels 490 or 490^a, to register thereon the amount set up on the keyboard.

15 Near the end of its return stroke, the main drive shaft causes the trip rod 303 to actuate the counter-disengaging and supporting means (not shown) to lift the axle 400 and disengage the active set of numeral wheels from the racks subsequently to the retirement of the latter, and hold the counters in such disengaged position.

20 The positioning bars 310 (Fig. 1), as they advance under the influence of the drive springs 383, rock the rear supporting arms 311, which are each provided with extensions 311^a. Links 515 connect these extensions with type-carriers 514 equipped with rows of types 561 corresponding with the numeral keys 117 in each row or denomination.

30 The projected stops 115 arrest the positioning bars 310 when the types 561 corresponding to the keys depressed, arrive at the printing line on a platen 2094, after which a universal latch 518 fast on a shaft 502, is caused to release printing hammers 510 journaled on a cross shaft 500. The hammers drive firing pins 562^a against the positioned types 561 to effect the imprint on the paper, of the amount set up on the keyboard.

40 The platen is supported on a shaft 2004 journaled in end frames 2010 secured to a slide 2065 shiftably mounted between ways 2067, and forming a carriage, the adjustment of which along the ways 2067 enables 45 the operator to print in any desired column on the paper.

Suitable mechanism (not shown) feeds the paper in line spacing direction.

45 A clearing key 327 and a total key 327^a operate mechanism (not shown) to vary the time of engagement and disengagement of the numeral wheels and racks, in the usual manner, to effect total printing, and to clear the machine, respectively.

55 To select which set of numeral wheels or counters shall become active, and to retain the remaining set or sets of counters inactive, there have been provided counter-selecting cross heads 418^a mounted on the upper ends of levers 418 fastened near the opposite ends of a suitably journaled cross shaft 402. The cross heads 418^a are of sufficient width to extend beneath both axles 400 of the two sets of counters herein shown for 60 illustration, when the levers are in their

intermediate positions, and are preferably slotted, as at 418^b, to embrace the opposite ends of the axle of one or the other set of counters when the heads are shifted to either side of their intermediate positions, to thereby lock such set of counters out of operation. Shifting the levers 418 to one side or the other of their intermediate position, displaces the heads 418^a from beneath the set of counters selected for operation, and permits the latter to engage the racks 410 at the proper time.

65 Manual counter-selection is effected by the adjustment of a handle 418^c which may be connected to one of the heads 418^a.

An interlocking mechanism is provided to prevent attempts to change the counter-selection adjustment after the main drive shaft 200 has started on its forward stroke, and further, to prevent an operation of the main drive shaft when the counter-selecting heads are not located in one or another of their adjusted positions.

70 Considering first the means which prevents an attempt to start the main drive shaft 200 on its forward stroke during an adjustment of the counter-selecting mechanism, and when the counter-selecting mechanism is not in a properly adjusted position,

75 a link 421^b (Figs. 1 and 2) conveniently secured to one of the counter-selecting heads 418^a, connects the counter-selecting mechanism with a swinging control plate 421^a which may be journaled on one of the well-known removable through-rods 102 used in the Wales machine to secure the keyboard in place. A stud 354^a projecting inwardly from the control plate 421^a, lies to one side or another of either of a pair of abrupt cams 422^a, 422^b carried on the rearwardly extending arm of a lever 422 fast on the inner end of a stub shaft 457^a mounted in one of the usual side frames. A spring 388^a presses the rearwardly extending arm of the lever 422 upwardly against the stud 354^a.

80 As seen in Fig. 1, when the counter-selecting mechanism is in its intermediate position, in which it holds both sets of counters 490, 490^a out of engagement with the racks 410, the stud 354^a lies in the recess between the two cams 422^a, 422^b. Shifting the counter-selecting mechanism to one or the other of its extreme positions, actuates the link 421^b to swing the control plate 421^a in one direction or the other, and thereby wipe the stud 354^a over one or the other of the cams 422^a, 422^b until it lies on the opposite side thereof (see Fig. 2).

85 The stud, as it wipes over the sharp cam rises, depresses the rear arm of the lever 422 bearing such cams, against the tension of the restoring spring 388^a, not only elevates the forward arm of the lever, but also turns the stub shaft 457^a.

90 A link 423^b connects the forward arm of

the lever 422 with the tail of a dog 423 journaled on a guide pin 954^b, and a spring 486^b (Fig. 2) inferior to the spring 388^a, tends to engage the tooth 423^m of the dog 423 with the notches in the usual full stroke segment 210^f fastened to, and turning with, the main drive shaft 200.

Normally the spring 388^a retains the forward arm of the lever 422 and the link 423^b in their lowered positions, to hold the dog 423 in idle position, but when the forward arm of lever 422 rises, it releases the link 423^b and frees the dog to the action of its spring 486^b, which thereupon snaps the dog 423 into engagement with the full stroke segment 210^f to lock the main drive shaft against rotation during the adjustment of the counter-selecting mechanism.

As the counter-selecting mechanism reaches one or another of its predetermined positions, the stud 354^a rides off of the cam 422^m or 422^p, to release the lever 422 and stub shaft 457^a to the action of the spring 388^a, which thereupon restores the lever to normal position and lowers the forward arm and link 423^b to disengage the pawl 423 from the full stroke segment 210^f against the tension of the lighter spring 486^b.

To enable the locking dog 423 and link 423^b to be operated independently of the lever 422, I provide a pin and slot connection 350^m between the lever and the link 423^b.

In motor-driven machines, it is common to start the machine by simply touching a key, as fully set forth in U. S. Patents to Küntzler, 1,080,515, December 2, 1913 and 1,151,803, August 31, 1915; Hunter and Küntzler, 1,093,424, April 14, 1914; and Wilius, 1,150,916, August 24, 1915, to which reference is made for a more comprehensive understanding thereof.

When machines are adapted for both manual and motor operation, it is customary to remove the handle by which the manual operation is effected, when the machine is to be motor-operated, and to apply the handle when the machine is to be manually-operated. It has been found advisable to arrange that the removal of the handle from the machine shall render the full stroke segment ineffective, and that the application of the handle shall render the full stroke segment effective, as set forth for example in U. S. Patent to Küntzler, 1,074,054, September 23, 1913. Hence, the counter-selecting mechanism-controlled dog 423 operable upon the full stroke segment will be ineffective to prevent the operation of the machine by the motor during an adjustment of the counter-selecting mechanism, and when the counter-selecting mechanism is left in an improper position.

To render such improper operation impossible, the stem of the depressible starting

key 915^d, which controls the connection of the motor and drive shaft 200, and which is slotted to accommodate upper and lower guide pins 954^b and 962^b, respectively, carries an auxiliary stem 915^a pivotally connected thereto at 350^a (Fig. 2), and terminating at its lower end in a stop flange 915^m, adapted to coact with an arresting arm 422^b, preferably hook-shaped to engage the stop flange. The stop flange normally lies in line with the pivot 350^a.

The arresting arm is secured to turn with the stub shaft 457^a which, it will be remembered, is rotated in one direction, as the control stud 354^a rides over the cams 422^m, 422^p, on lever 422, and in the other direction by the superior spring 388^a (Fig. 2).

Normally, the spring 388^a retains the arresting arm 422^b in idle position, but as the control stud 354^a rides over either cam 422^m or 422^p, it rocks the lever 422 and shaft 457^a to swing the hooked end of the arresting arm into the path of the stop flange 915^m on the auxiliary stem 915^a of the starting key and thereby prevent depression thereof. A spring 281^m (Fig. 2) normally holds the upper end of the auxiliary stem 915^a against the guide stud 954^b to retain the stop flange 915^m in position to strike the arresting arm 422^b, when the latter shifts to effective position, in case depression of the starting key is attempted.

As the counter-selecting mechanism reaches its properly adjusted position, the control stud 354^a rides off the cam 422^m or 422^p and releases the lever 422 and shaft 457^a to the action of their spring 388^a, which returns the parts to normal position and swings the arresting arm 422^b to idle position.

Depression of the starting key 915^d shifts the stop flange 915^m into the path of the hook on the arresting arm 422^b to block the latter and hence hold the lever 422 against rocking, to lock the counter-selecting mechanism in set position.

To prevent attempts to adjust the counter-selecting mechanism from one position to another while the main drive shaft 200 is in operation, it is convenient to lock the lever 422 in its normal elevated position.

This is accomplished by providing a latch 423^d journaled on a pin 260^f and pressed by a spring 289 into position beneath the rearwardly extending arm of the lever 422 or a block 491 projecting therefrom.

The total locking mechanism disclosed in U. S. patent to Bickford, 1,086,580, February 10, 1914, is utilized to restrain the latch 423^d in idle position. A link 214^b connects the cross rod 303, which, it will be remembered, swings forwardly and backwardly at each operation of the machine, with the total locking plate 212^b at 259^f. The locking plate is also journaled on the pin 260^f. The

pin 259^c, connecting the link 214^b and the locking plate 212^b, projects into the path of a lug 423^a on the latch 423^a. When the machine is idle, at which time, the rod 303 and locking plate 212^b are at the rear ends of their paths of travel, (see Fig. 1) the pin 259^c is in contact with the lug 423^a and restrains the latch 423^a in its idle position, against the tension of its spring 289.

As the main drive shaft turns on its forward stroke, (see Fig. 2), it advances the swinging cross rod 303 through the links 214, and the cross rod, in turn, swings the locking plate 212^b forwardly by means of the link 214^b, thereby withdrawing the pin 259^c from the path of the lug 423^a to release the latch 423^a to the action of its spring 289. The spring immediately snaps the latch to effective position beneath the rearwardly extending arm of the lever 422 to lock the stud 354^c on the control plate 421^a against movement and hence, prevent adjustment of the counter-selecting mechanism.

The main drive shaft on its return stroke, swings the radius bars 323 and rod 303 rearwardly, with the link 214^b and lock plate 212^b, and the stud 259^c near the end of such return stroke, strikes the lug 423^a to withdraw the latch 423^a to idle position and free the counter-selecting mechanism for operation.

Reference is directed to the above-mentioned pending applications of Pentecost and Fisher for a more comprehensive understanding of the foregoing, which constitutes a part of the present invention only in so far as it is combined with the novel features hereinafter explained.

In the commercial operation of calculating machines, it is frequently desired to print a series of items across a sheet, some of which items it is desired to accumulate in one or another set of counters, and others of which are to be printed only.

To render unnecessary the manual shifting of the counter-selecting mechanism, and to enable the user to perform his work in a shorter period of time, as well as to eliminate the necessity for charging his mind with the manual selection of the proper set of counters at the proper time, I have arranged a simple and novel means controlled by the carriage to automatically effect the selection of the proper set of counters on which to register the items. Thus the carriage, as it shifts to the column in which it is desired to print an item, will set mechanism which, upon the operation of the main drive shaft, will automatically select the set of counters in which it is desired to accumulate such item.

Furthermore, I have contrived to utilize the identical counter-selecting mechanism under control of the carriage, to render all sets of counters incapable of accumulating

an item, which may consist of a designating number only, the addition of which is not desired.

While I have illustrated my invention as applied to a two-counter machine, it will be understood that the device is applicable, with the necessary alterations, to machines equipped with a larger number of sets of counters.

Since the same mechanism which selects any of the sets of counters for operation is also utilized to prevent accumulation on all sets of counters, a single explanation will cover both operations, and to enable one to more clearly understand the explanation and the claims, I have designated the elements by which I attain the above results as the actuating mechanism, the driving mechanism operated thereby, the coupler to releasably connect the actuating and driving mechanisms; the adjustable transmitting mechanism shifted by the drive mechanism and operable upon the counter-selecting mechanism to effect counter-selection; and the carriage control of such transmitting mechanism.

Other features forming a part of my invention, will also be referred to as the explanation proceeds.

In the present form of my invention, the actuating mechanism (best shown in Fig. 3) includes a bell-crank actuating lever 419ⁱ journaled on a cross shaft 1801 located at the rear of the machine, the longer forwardly projecting arm of the lever terminating in a head having an arcuate slot 419^r formed therein to accommodate a spacing stud 250^b projecting from the adjacent rocker 220, alongside which the lever extends. A washer or head 1614 on the outer end of the stud overlies the outer face of the lever and co-operates with the collar adjacent the inner face of the lever, to guide the latter in its travel relatively to the rocker, and to retain the lever at a constant distance therefrom.

The slot 419^r is made wider than the diameter of the stud 250^b to compensate for the different arcs of travel of the rocker 220 and lever 419ⁱ, respectively, due to the difference in centers.

A carrier 419^s pivotally secured at 257, to the head of the actuating lever 419ⁱ, extends rearwardly alongside the inner face of the lever, and supports a cam block 419^a at its free end. A pin 353ⁱ mounted in the carrier, passes through a slot 419^s in the head of the actuating lever 419ⁱ, and a spring 480 connected to the protruding end of the pin and to the lever 419ⁱ, normally holds the pin 353ⁱ at the lower end of its slot, to yieldingly retain the cam 419^a in the path of a wiper 354^b projecting from the adjacent radius bar 323.

As the radius bars 323 advance on the

forward stroke of the main drive shaft (Fig. 2), the wiper 354^b strikes the opposing upwardly inclined cam face of the block 419^c, and proceeds to ride therealong. As 5 the pin 353^c is at the lower end of its slot 419^c, the carrier 419^c cannot yield relatively to the actuating lever 419ⁱ and consequently the pressure of the wiper against the cam rocks the forwardly extending arm of the 10 actuating lever downwardly against the tension of a restoring spring 480^a, and the upwardly extending arm 419^w of the lever rocks forwardly.

The wiper reaches the apex of the abrupt 15 cam 419^c shortly after the main drive shaft starts on its forward stroke and then rides down the forward face of the cam, thereby relieving its pressure on the cam, to enable the actuating lever to rise under the influence 20 of its spring 480^a, until it is arrested by contact with the cross rod 508^a under which the lever passes or by a collar thereon. This results in imparting a short snappy oscillation 25 to the actuating lever, which returns to normal position early in the forward stroke of the main drive shaft.

The wiper 354^b, upon its return stroke, which occurs coincidently with the return of the main drive shaft, strikes the forward 30 lower edge of the cam 419^c, which is interposed in the path of return of the wiper by the restoration of the actuating lever, and raises the cam and the carrier 419^c against the tension of spring 480, which latter re- 35 stores the carrier and cam to normal position, as soon as the wiper, traveling along the lower flat face of the cam, clears the rear end of the latter.

It will be noted that the actuating mechanism 40 functions at each operation of the machine.

The actuating mechanism is adapted to operate a driving means, which, in the present instance, includes a bent arm 419^a (best 45 shown in Fig. 3) journaled on, and extending upwardly from, the cross shaft 1801, which arm supports a substantially triangular drive member 419ⁱ pivotally mounted on one of its angles, at 350^b intermediate the 50 ends of the arm 419^a. A check lug 419^t on the arm, projects laterally in front of the vertical forward face of the triangular member 419ⁱ, and a spring or flexible link 480^a yieldingly holds the triangular drive member 55 against the check lug. A weaker spring 480^b connected to the supporting arm 419^a, normally holds the drive mechanism (including the arm 419^a and member 419ⁱ) in its rearward position against an arresting 60 stud 461^c.

A coupler 419^e, pivoted at 350 to the bent supporting lever 419^a, releasably connects the actuating and driving mechanisms. The coupler, in the present instance, is sub-

stantially U-shaped, one branch of the coupler terminating in a hook or lip 419^e adapted to engage an ear 419^v on the upwardly extending arm 419^w of the actuating lever 419ⁱ, the remaining branch of the coupler having formed therein an arcuate slot 419^r 70 to accommodate a stud 461^a mounted on an arm 419^d extending rearwardly from one end of a bail 419^b journaled on a cross rod 903^c. The spring 480^c connected to the bail, normally holds the rearwardly extending 75 arm 419^d depressed and the hooked end 419^e of the coupler disengaged from the ear 419^v on the actuating lever, as shown in Fig. 1.

To enable the operator to couple and uncouple the actuating and driving mechanisms, at will, I provide the inner end of the bail 419^b with a forwardly projecting arm 419^r (Fig. 3) carrying a stud 2451^c entered in a slot 1 in the stem 419^c of a key 492 (Figs. 1 and 2). A spring link 685 connects 85 the stud 2451^c and key stem, and normally holds the key elevated.

Depression of the key 492 tensions the spring 685 connected to the forwardly projecting arm 419^r of the bail 419^b, to turn the 90 bail on the cross rod 903^c and swing its rearwardly extending arm 419^d upwardly. The stud 461^a in such rearwardly extending arm, travels toward the outer end of the arcuate slot 419^r in the upper branch of the coupler 95 419^e, to rock the lower branch of the coupler upwardly and interpose the hook 419^e into the path of the ear 419^v of the actuating lever 419ⁱ. The actuating lever is thus enabled to draw the supporting arm 419^a and 100 driver 419ⁱ forwardly against the tension of the restoring spring 480^a. The arcuate slot in the upper arm of the coupler 419^e, conforms to the path of travel of the coupler when operated by the actuating lever, to prevent disengagement of the coupler relatively 105 to the lever 419ⁱ, due to such travel.

The drive means may conveniently operate the counter-selection mechanism in the 110 following manner.

The upper end of the driver member 419ⁱ terminates in a forwardly projecting head 2, provided with two diverging series of graduated shoulders 3, 3', 4, 4', one series 3, 4 being stepped upwardly from a separating 115 nose 5, and the other series of corresponding shoulders 3', 4' being undercut from the nose.

The foremost shoulders 3, 3' and the rearward shoulders 4, 4' lie in parallel vertical 120 planes.

The ascending shoulders 3, 4 are adapted to strike an impact face 6 formed on the free rear end of a forwardly extending transmitting feeler 419^a connected at 461ⁱ to the 12 counter-selecting lever 418 above its pivotal support 402, and the undercut shoulders 3', 4' contact a similar impact face 6 on the

- free end of a second transmitting feeler 419 connected at 264 to an extension 418^a of the counter-selecting lever 418, depending below its pivotal support. 65
- 5 The nose 5 extends between the rear ends of the feelers 419^a, 419 to prevent positioning either of the transmitting feelers relatively to the shoulders appropriated to the other feeler. 70
- 10 The transmitting feelers are slotted intermediate their ends to embrace supporting and guide studs 461^a, 461^b projecting from the opposite arms of a Y-shaped adjusting member 419^c fast on a cross shaft 406, journaled in one of the side frames 969^a (Fig. 5) and in the printer side frame 565. A spring 480^c normally returns the adjusting member 419^c to, and holds it in, lowered position, which position is determined by the contact 15 of an arresting finger 7 projecting from the lower transmitting feeler 419, with the shaft 903^c, as shown in Fig. 1. 75
- 20 With the parts as thus far explained, positioned as shown in Fig. 1, it is evident that depression of the key 492 renders the coupler 419^c effective to connect the actuating and driving mechanisms. The key is provided with the usual notch adapted to engage the customary casing (not shown) to 25 lock the key in depressed position, and thus retain the parts where adjusted. 80
- 25 Turning the main drive shaft 200, on its forward stroke, imparts a snappy oscillation to the actuating mechanism at the outset of such forward stroke, which oscillatory movement is communicated to the flexible drive mechanism through the coupler 419^c, to rock the latter including the drive member 419ⁱ forwardly against the tension 30 of the restoring spring 480^b. 85
- 30 In case the impact face 6 of either of the transmitting feelers 419^a, 419, has been adjusted to lie in the path of its respective series of shoulders 3, 4 or 3', 4', the active shoulder, during the forward travel of the drive member 419ⁱ, strikes such impact face and advances the transmitting feeler to shift 35 the counter-selecting members 418 to select another set of counters for coaction with the racks 410 and restrain from operation the set which, otherwise, would have become effective, or, depending upon the adjustment of the feelers, the drive mechanism may shift 40 the counter-selecting members to their intermediate position to restrain all of the counters from operation. 90
- 35 The path of travel of the supporting arm 419^a is slightly longer than is necessary to cause the driving member 419ⁱ to shift the counter-selecting members 418 from one extreme position to the other, in order to insure the complete switching of the members, and the members when arrested in their extreme positions, oppose further movement 45 of the driving member 419ⁱ, so that the excess portion of the throw of the arm 419^a upon the arrest of the drive member 419ⁱ merely results in stretching the flexible link or spring 480^d connecting the supporting arm 419^a and the drive member 419ⁱ. 95
- 50 The return of the actuating lever 419^c, under the action of its restoring spring 480^c, frees the drive mechanism to the action of its restoring spring 480^b, which immediately returns the drive mechanism to its normal position. 100
- 55 To automatically shift the adjuster 419^c to vary the positions of the feelers 419, 419^c relatively to their respective series of shoulders 3, 4', and 3', 4, and thereby effect changes in the position of the counter-selecting members, upon the operation of the machine, I conveniently provide the adjuster, or the shaft 406 to which the adjuster is secured, with a switch toe 419^b adapted to lie in contact with a presser foot 2029^m (best shown in Fig. 5) projecting from a horizontally arranged lever 2029^e pivoted at 2062, to the bottom face of the lower carriageway 2067. 105
- 60 The free end of the lever 2029^e terminates in an outward extension 2029^e carrying a stud 354, and the restoring spring 480^c of the adjuster 419^c, forces the switch toe 419^b against the presser foot 2029^m to hold the extension 2029^e with its stud 354 in their extreme rearward positions, a pin 2062^b (Fig. 5) which depends from the under face of the lower carriageway 2067 and passes through a closed slot 2029^p in the lever 110 2029^e, operating to limit the throw of the lever and stud in opposite directions. 115
- 65 The stud 354 is thus held in the path of travel of one or another of a series of inwardly extending tappets 2018^a, 2018^c adjustably mounted on a toothed supporting bar 2092^a suspended from brackets 2026^a fastened to and projecting from the opposite ends of the carriage slide 2065. The tappets 2018^a and 2018^c are of different lengths 120 to rock the intermediate lever 2029^e varying distances, and the lever and its presser foot 2029^m, in turn, will swing the switch toe 419^b inwardly or allow it to return outwardly, because of the tension of the spring 480^c, to turn the shaft 406 and raise or lower the adjuster 419^c, and thereby vary the positions of the impact faces 6 of the transmitting feelers 419^a, 419, relatively to the stepped head 2 of the driving mechanism. 125
- 70 The tappets 2018^a and 2018^c are located along the supporting bar 2092^a in such relation to the usual tabulating stops (not herein shown) that, as the carriage feeds from column to column, certain of the tabulating stops which arrest the carriage in position to permit printing in the respective columns, will also locate one or another of the

tappets 2018^a, 2018^c in contact with the stud 354 to shift the adjuster to position the proper transmitting feeler relatively to one or another of the shoulders on the driving head.

A concrete example of one of the classes of work for which this mechanism is adapted will more clearly illustrate its operation.

It is often desired to list debits in one column, and accumulate them on one set of counters, to list credits in another column, and accumulate them on a second series of counters, and to print a designating figure, date, item, or what not in another column which is not to be accumulated.

A convenient form, and one which is frequently used, is as follows:

No.	Cost price.	Selling price.
4382	19.71	22.50
7186	43.07	75.80
9271	7.92	18.00

In performing this example, the carriage will first be located so that the usual tabulating stop which holds the carriage at the right hand end of its travel, will position the column in which designating members not to be accumulated, are listed, opposite the types 561. In such position, the carriage will also locate one of the shorter tappets 2018^c in contact with the stud 354 on the intermediate lever 2029^e, as shown in Fig. 5, to hold the latter partway between its inner and outer limits of throw, against the tension of the restoring spring 480^c.

Under such adjustment, the lever 2029^e will have rocked the switch toe 419^b forwardly to turn the shaft 406 and raise the adjuster 419^c from its lowest position (shown in Fig. 1), which it occupies when none of the tappets are in contact with the stud 354, to its intermediate position (Fig. 3), and the adjuster will have located the impact faces 6 of the transmitting feelers 419^d, 419^e in line with the rearmost shoulders 4, 4'.

Providing the counter-selecting heads 418^m are at one or the other of their extreme limits of travel, the impact face 6 of one or the other of the feelers will lie within the path of its shoulder 4 or 4', while the remaining feeler lies in line with its shoulder 4 or 4', but just outside its path. Upon starting to operate the machine, the control key 492 being depressed, the actuating lever 419^j will be rocked downwardly against the tension of the spring 480^b, to advance the driving head 2 idly through a part of its stroke, against the tension of the spring 480^b, and cause it to strike the impact face 6 of the nearest feeler, to thrust the latter forwardly and shift the counter-selecting heads 418^m to their intermediate position, wherein

they prevent the engagement of both sets of 65 counters 490, 490^x with their racks 410.

When the driving head 2 thrusts forwardly the particular feeder 419^d or 419^e which has been adjusted to operative position, to shift the counter-selecting member 70 418, the remaining feeler shifts idly rearwardly, until at about the conclusion of the shifting operation, the impact face of the idle feeler contacts its appropriate drive shoulder, after which any further travel of 75 the drive member 419ⁱ will serve to center the counter-selecting member 418 in its intermediate position.

The wiper 354^b operates the actuating lever 419^j early in the forward stroke of the main drive shaft 200, to shift the counter-selecting heads 418 to their predetermined positions, and then releases the lever to the action of its spring 480^b which restores the lever and enables the spring 480^b to retire 85 the driving mechanism to idle position.

The positioning bars 310 will advance until arrested by the projected stops 115, or the detents 221, the bars in turn advancing the racks 410, and elevating the proper type-carriers 514 to position types 561 at the printing line.

Near the end of the forward stroke, the printing hammers 510 will be released to impress the positioned types on the paper, 95 but the heads 418 will restrain counters 490 and 490^x from dropping into mesh with the racks.

The main drive shaft on its return stroke, retires the positioning bars and racks, and 100 the bars lower the type-carriers.

If the counter-selecting heads 418^m stood in their intermediate positions (as in Fig. 3) prior to the operation of the machine, then the impact faces 6 of the transmitting 105 feelers would each lie just at the end of the forward travel of the shoulders 4, 4', and the latter would merely serve to confirm or insure the accurate location of the counter-selecting members 418 in such intermediate 110 position.

As the paper carriage shifts to the next column, the shorter tappet 2018^c releases the stud 354, whereupon the spring 480^c draws the adjuster 419^c to its lowest position and 115 forces the stud 354 further outwardly into the path of the next succeeding tappet 2018^a, for instance.

The depression of the adjuster 419^c lowers the impact face 6 of the upper feeler 419^d 120 into line with the forward drive shoulder 3 (see Fig. 1) and the impact face 6 of the lower feeler 419 drops to a point below and out of the path of the drive shoulder 4'.

It will be noted that no tappet controls 125 this position of the parts, and after the operator sets up the cost price on the keyboard, an operation of the machine will

cause the drive mechanism to shift the counter-selecting heads 418^m to the extreme forward end of their travel, to free the rear set of counters 490^c for operation and restrain the front set 490 from engagement with their racks 410.

During this operation, the driving head 2 will clear the lower feeler 419 by reason of the displacement of the latter relatively to its shoulder 3', but such lower feeler will be shifted rearwardly as the counter-selecting heads travel forwardly, in position to be adjusted into the path of its shoulder 3' in case the next adjustment should locate it in such position, in order to partake of substantially the entire advance of the shoulder 3', just as the upper feeler 419^d partakes of substantially the entire travel of the drive shoulder 3 in the operation just described.

During this operation of the machine, the cost price will be listed in its appropriate column and registered in the rear set of counters 490^c, in the manner heretofore explained.

As the carriage feeds to the next column, it brings the long tappet 2018^a into contact with the stud 354, to force the lever 2029^e to the forward end of its travel, which lever, in turn, lifts the adjuster 419^c from its lowest to its highest position, to raise the impact face 6 of the upper feeler 419^d above and out of the path of the driver head 2, and to locate the impact face 6 of the lower feeler 419 directly in front of its shoulder 3'.

After the selling price is set up on the keyboard, the machine is operated, and at the outset of its operation, the drive mechanism thrusts the lower feeler 419 forwardly to shift the counter-selecting member 418 from one extreme position to the other, to restrain the formerly operative counters in idle position, and to release the formerly idle counters for operation. The selling price will have been listed in its column and registered in its set of counters 490 at the conclusion of the operation of the machine.

Of course, if it is desired at any time to repeatedly add amounts in a single set of counters, but to enter such amounts in successive columns, all that is necessary is to either locate a corresponding number of long tappets 2018^a in position to contact the stud 354 as the successive columns are brought to printing position, or else to omit tappets from a series of corresponding column positions, depending upon which set of counters are to be active. Or, if items printed in successive columns in cross tabulating, are to be non-added, a corresponding number of short tappets 2018^c are located on the bar 2092^e in position to successively control the lever 2029^e, as the carriage brings the successive columns to printing position.

Another method to which the operator 65 might resort, should he desire to retain the counter-selecting means against automatic operation, is to grasp and hold the handle 418^p in the desired position to release the proper counters for operation.

The exercise of such restraint on the handle, will result in causing the impact face 6 or 6' of the particular feeler 419^d or 419 against which the driving head 2 impinges, to act as a check to prevent the complete 75 advance of the driving head. The throw of the supporting arm 419^a, however, is not restricted, and the latter will rock as usual against the tension of the restoring spring 480^b, and also against the tension of the 80 flexible link 480^d which connects the arm and the driving member 419ⁱ.

The operator may shift the counter-selecting members 418 to any of their positions by manipulating the handle 418^p regardless of 85 the positions of the feelers 419^d, 419, or of the tappets 2018^a, 2018^c, but it may be necessary to retain the handle manually in shifted position, during the first part of the operation of the machine, depending upon whether or 90 not the adjusting mechanism is set to effect a different positioning of the counter-selecting members.

Of course, releasing the control key 492 severs the connection between the actuating 95 and drive mechanisms, by relaxing the tension of the spring 685 and freeing the bail 419^b to the action of its spring 480^a, which rocks downwardly the rear arm 419^a of the bail, and the arm swings the coupler 419^c 100 downwardly, to displace the hook 419^e relatively to the ear 419^f on the actuating lever 419ⁱ, as shown in Fig. 1. Under this adjustment the drive mechanism remains idle during operations of the machine.

Obviously, the tappets 2018^a, 2018^c may be arranged in any desired succession to accommodate different forms.

Attention is also directed to the fact that the tappets merely control the position of the adjusting and transmitting mechanism, through which the counter-selecting heads are shifted, the actual power to shift the counter-selecting mechanism being derived from the main drive shaft of the machine.

In view of the fact that the automatic counter-selection takes place after the main drive shaft starts on its forward stroke, it is necessary to disable the locks which prevent manual adjustment of the counter-selecting mechanism after the main drive shaft has started.

This I conveniently accomplish by providing a rearwardly extending link 523^d having at its forward end a loose pin and 125 slot connection 264^m with the tail of the latch 423^d, and connected at its rear end to the lower arm of a bell crank lever 419^o

5 journaled on a stud 562. A short link 420^a connects the upper arm of the bell crank lever 419^a with an arm 8 projecting forwardly from the coupler-controlling bail 419^b, the short link 420^a and upper arm of lever 419^a forming a toggle mechanism.

10 Depression of the key 492 rocks the bail 419^b, as heretofore explained, and lowers the forwardly projecting arm 8 to rock the lever 419^a and thrust the link 523^d forwardly. The link swings the latch 423^d rearwardly to restrain it in idle position against the tension of its drive spring 289, so that when the restraining stud 259ⁱ, on its advance, 15 releases the latch, the latter cannot assume its effective position.

15 The pin and slot connection 264 between the latch and link 523^d permits operation of the latch relatively to the link when the control key 492 is in elevated position.

20 Furthermore, the latch 423^d carries a pin 254^b, which, when the latch swings rearwardly upon the depression of the control key 492, rides along a cam edge 420^m terminating in a dwell portion, formed on the rear end of a disabling lever 420^c pivoted on the stub shaft 457^d, to rock the lever 420^c. The forward end of the disabling lever has a pin and slot connection 253 with the link 25 423^b extending between the oscillatory lever 422 and the dog 423, and when the pin 254^b rocks the disabling lever 420^c, the latter draws the link 423^b downwardly relatively to the lever 422 and displaces the dog 423 35 relatively to the full stroke segment 210^f.

30 When the control bail 419^b restores to normal position under the influence of the spring 480^a, upon the release of the key 492, the arm 8 rises, drawing with it the link 420 to rock the bell crank 419^a and shift the link 523^d to release the latch 423^d for operation.

35 Since the counter-selecting mechanism operates during the first part of the forward stroke of the main drive shaft, and also since, in totaling and clearing operations, the counters are meshed with their racks at substantially the same period in the operation of the machine, it is obvious that, to 40 avoid conflict or interference between the counter-selection, and the totaling and clearing operations, it is advisable to disable the automatic counter-selecting mechanism when totaling or clearing operations are to 45 be performed, and thus prevent interruption of the operation of the machine, or injury thereto.

45 Therefore, I conveniently arrange to disable the coupler 419ⁱ upon the depression of either the total key 327^b (Fig. 1) or the clearing key 327.

50 In the before-mentioned Pentecost and Fisher application, filed July 17, 1918, Serial No. 245,273, and as shown in Fig. 1, the clearing and the total keys are provided

5 with wiping studs 352^b and 352^m, respectively, adapted to ride along inclines 326^m and 326^b of different lengths formed on the forward end of a longitudinally extending thrust bar 326^d, which forward end lies beneath the total and clearing key stems. A 70 crank 1814 connects the rear end of the thrust bar to the cross shaft 1801 on which is mounted means (not herein shown) to position different sign printing types (also not 75 shown) at the printing line.

Depression of either key 327^b or 327 will turn the shaft 1801, the only difference in this respect, being that depression of the clearing key 327, whose stud 352^b rides along 80 the shorter incline 326^m, will turn the shaft 1801 through a lesser angle than will the total key 327^b.

I contrive to utilize the shaft 1801 to disable the automatic counter-selecting mechanism, by mounting thereon a tripper 324^d and providing the coupler-controlling bail 419^b with a depending trigger 9. Depression of the control key 492, which rocks the bail to set the coupler to effective position, 90 swings the free end of the depending trigger 9 to a point closely adjacent to or in contact with the tripper 324^d, (see Fig. 3).

With the trigger 9 in such position, depression of either the total or clearing keys 95 swings the tripper 324^d against the trigger to press the latter forwardly and rock the controlling bail 419^b against the tension of spring 685, the stud 2451^c traveling upwardly in the slot 1 of the controlling key 100 stem 419ⁱ, provided to permit this operation, it being remembered that the key stem remains locked in depressed position.

Such enforced rocking of the bail depresses its rearwardly projecting arm 419^a 105 carrying the operating stud 461^a to cause the latter to swing the upper branch of the coupler 419ⁱ downwardly and displace the lip 419^s of the coupler from in front of the lug 419^v on the shorter arm 419^w of the 110 actuating lever 419ⁱ. The actuating lever is thus prevented from operating the drive mechanism, and hence the counter-selecting mechanism is rendered inactive, irrespective of the position of the feeler-adjusting mechanism and of the carriage, as well as the control key 492.

The controlling bail 419^b, when rocked by the tripper 324^d, operates through the toggle link 420^a, lever 419^a, and connecting link 120 523^d to release the latch 423^d to the action of its spring 289, which restores the latch to normal position, thereby rendering the disabling lever 420^c ineffective to hold the dog 423 inoperative.

125 At the conclusion of a totaling or clearing operation, the keys 327^b or 327 rise to enable the draft link 326^d to return to normal position, thereby withdrawing the tripper 324^d, whereupon spring 685 reverses the position 130

of the bail 419^b to restore the coupler to operative position, and to restrain the latch 423^d so as to render the disabling lever 420^c effective.

5. It will be understood that the paper carriage may be manually shifted, or may be drawn in one direction by the usual spring drum, and tripped automatically or by hand, to bring the successive tappets to effective 10 position.

Changes may be made in the form and arrangement of the several parts set forth, without departing from the spirit and scope of the invention.

15. What I claim is:—

1. In a multiple counter calculating machine, the combination with counter-selecting mechanism adapted to free one or another of the sets of counters for operation; 20 and a shiftable paper carriage; of drive mechanism for the counter-selecting mechanism, actuating mechanism functioning at each operation of the machine; a coupler to releasably connect the actuating and drive mechanisms; manually-operable means to control the coupler; adjustable transmitting members operable by the drive mechanism, to shift the counter-selecting mechanism; an adjusting member for the transmitting members to shift the latter relatively to the drive mechanism; and means controlled by the carriage to position the adjusting member.

2. In a multiple counter calculating machine, the combination with counter-selecting mechanism adapted to free one or another set of counters for operation; a main drive shaft; and a shiftable paper carriage; of drive mechanism for the counter-selecting mechanism; means to effect the operation of the drive mechanism at will from the main shaft; adjustable transmitting members operable by the drive mechanism, to shift the counter-selecting mechanism to one or another of its positions; an adjusting member to position the transmitting members relatively to the drive mechanism; and means controlled by the carriage to variably locate the adjusting member.

3. In a multiple counter calculating machine, the combination with counter-selecting mechanism adapted to free one or another set of counters for operation; and a shiftable paper carriage; of an actuating lever; a cam shiftably connected to the actuating lever; means to limit the travel of the cam relatively to the lever; means to yieldingly retain the cam at one limit of its travel; a driving wiper adapted, at each operation of the machine, to ride over the cam to rock the lever, the wiper on its return, adapted to displace the cam against the tension of its yielding retaining means; drive mechanism operable by the actuating lever; 60 adjustable transmitting members operable

by the drive mechanism to shift the counter-selecting mechanism; and means controlled by the shiftable paper carriage to adjust the transmitting members to enable the drive mechanism to variously position the counter-selecting mechanism.

4. In a multiple counter calculating machine, the combination with counter-selecting mechanism adapted to free one or another set of counters for operation, and a shiftable paper carriage; of means to automatically operate the counter-selecting mechanism, including an actuating lever; a cam on the lever; a driving wiper adapted at each operation of the machine, to ride over the cam to rock the latter in one direction; means to restore the lever to normal position; drive mechanism operable by the lever; a releasable connection between the lever and drive mechanism; adjustable transmitting members operable by the drive mechanism, to shift the counter-selecting mechanism; and means controlled by the shiftable paper carriage to adjust the transmitting members to enable the drive mechanism to variously position the counter-selecting mechanism.

5. In a multiple counter calculating machine, the combination with counter-selecting mechanism adapted to free one or another set of counters for operation; and a shiftable paper carriage; of a drive mechanism for the counter-selecting mechanism; an actuating lever for the drive mechanism; means to positively drive the lever in one direction; means to restore the lever to normal position; adjustable transmitting members operable by the drive mechanism, to shift the counter-selecting mechanism; and means controlled by the shiftable paper carriage to adjust the transmitting members.

6. In a multiple counter calculating machine, the combination with counter-selecting mechanism adapted to free one or another of the sets of counters for operation; a shiftable paper carriage; and a main drive shaft; of a drive mechanism for the counter-selecting mechanism; an actuating lever for the drive mechanism; means operated on the forward stroke of the main drive shaft, to positively drive the lever in one direction; means to restore the lever to normal position during the same forward stroke of the main drive shaft; adjustable transmitting members operable by the drive mechanism, to shift the counter-selecting mechanism; and means controlled by the shiftable paper carriage to adjust the transmitting members.

7. In a multiple counter calculating machine, the combination with counter-selecting mechanism adapted to free one or another set of counters for operation; of an actuating mechanism; a drive mechanism, including a supporting arm; a coupler to releasably connect the arm and the actuating

mechanism; a driving head mounted on the supporting arm; flexible means to connect the arm and head against relative movement; adjustable transmitting members operable by the driving head, to shift the counter-selecting mechanism; and means to adjust the transmitting members, to enable the latter to variously position the counter-selecting mechanism.

8. In a multiple counter calculating machine, the combination with counter-selecting mechanism adapted to free one or another set of counters for operation; of a drive mechanism for the counter-selecting mechanism; an actuating mechanism for the driving mechanism; a coupler mounted upon one of said mechanisms to travel therewith, and to releasably engage the other of said mechanisms; means to control the coupler, and having a loose connection therewith to permit relative movement; adjustable transmitting members operable by the driving mechanism, to shift the counter-selecting mechanism; and means to variously adjust the transmitting members relatively to the drive mechanism, prior to the operation of the drive mechanism.

9. In a multiple counter calculating machine, the combination with counter-selecting mechanism adapted to free one or another set of counters for operation; of a drive mechanism for the counter-selecting mechanism; an actuating mechanism for the drive mechanism; manually-controlled means to releasably couple the actuating and drive mechanism; adjustable transmitting members operable by the drive mechanism, to shift the counter-selecting mechanism to its various positions; and means to adjust the transmitting members relatively to the drive mechanism, prior to the operation of the drive mechanism.

10. In a multiple counter calculating machine, the combination with counter-selecting mechanism adapted to free one or another set of counters for operation; of a drive mechanism for the counter-selecting mechanism; an actuating mechanism functioning at each operation of the machine; a releasable connection between the actuating and drive mechanism; adjustable transmitting members operable by the drive mechanism, to variously position the counter-selecting mechanism; and means to adjust the transmitting members relatively to the drive mechanism to determine the position to which the counter-selecting mechanism shall be shifted by the drive mechanism.

11. In a multiple counter calculating machine, the combination with counter-selecting mechanism adapted to free one or another set of counters for operation; of a flexible drive mechanism for the counter-selecting mechanism; an actuating mecha-

nism functioning at each operation of the machine; a releasable connection between the actuating and drive mechanisms; adjustable transmitting members operable by the drive mechanism, to variously position the counter-selecting mechanism; means to adjust the transmitting members to determine the position to which the counter-selecting mechanism shall be shifted by the drive mechanism; and means to restore the actuating and drive mechanisms to normal position.

12. In a multiple counter calculating machine, the combination with a plurality of sets of counters; drive members therefor; counter-selecting mechanism, shiftable to free one or another set of counters for operation; and a total key; of a drive mechanism for the counter-selecting mechanism; an actuating mechanism for the drive mechanism; a coupler to releasably connect the actuating and drive mechanisms; a special key to control the coupler, and having a loose connection therewith to permit relative movement; adjustable transmitting members operable by the drive mechanism to shift the counter-selecting mechanism to one or another of its positions; means to variously adjust the transmitting members relatively to the drive mechanism; and means operable by the total key to control the coupler independently of its special key and irrespective of the position of such special key.

13. In a multiple counter calculating machine, the combination with counter-selecting mechanism adapted to free one or another set of counters for operation; of a drive mechanism, having a series of ascending shoulders and a series of undercut shoulders; transmitting members adjustable relatively to the respective series of shoulders, and operable thereby, to variously shift the counter-selecting mechanism; and means to adjust the transmitting members.

14. In a multiple counter calculating machine, the combination with counter-selecting mechanism adapted to free one or another set of counters for operation; of a drive mechanism for the counter-selecting mechanism; transmitting members operable by the drive mechanism, to shift the counter-selecting mechanism, the transmitting members and drive mechanism being relatively adjustable to determine the position to which the counter-selecting mechanism shall be shifted; and means to effect such adjustment.

15. In a multiple counter calculating machine, the combination with counter-selecting mechanism adapted to free one or another set of counters for operation; of a drive mechanism for the counter-selecting mechanism; adjustable transmitting mem-

bers operable by the drive mechanism, to shift the counter-selecting mechanism; an adjusting mechanism connected with the transmitting members to render either member effective and the other ineffective; and means to control the adjusting mechanism.

16. In a multiple counter calculating machine, the combination with counter-selecting mechanism adapted to free one or another set of counters for operation; and a shiftable paper carriage; of a drive mechanism for the counter-selecting mechanism; adjustable transmitting members operable by the drive mechanism, to shift the counter-selecting mechanism to one or another of its positions; an adjusting member to position the transmitting members relatively to the drive mechanism; and means mounted on the carriage and adapted to variously operate the adjusting member to control the position of the transmitting mechanism.

17. The combination with a multiple counter calculating machine; of a pivotally mounted, counter-selecting mechanism adapted to free one or another set of counters for operation; transmitting members connected to the counter-selecting mechanism on opposite sides of its pivotal support, respectively; drive mechanism for the transmitting members; and means to adjust the transmitting members relatively to the drive mechanism to enable the latter to shift the counter-selecting mechanism to any of its positions.

18. The combination in a multiple counter calculating machine; of a counter-selecting mechanism adapted to free one or another set of counters for operation; a drive mechanism for the counter-selecting mechanism, transmitting members adjustable relatively to and operable by the drive mechanism, to shift the counter-selecting mechanism to one or another of its positions; and means to adjust the transmitting members.

19. In a multiple counter calculating machine, the combination with a counter-selecting mechanism; of an actuating mechanism; a drive mechanism operable thereby, and including a supporting arm; and a relatively movable driving head; transmitting members operable by the driving head to shift the counter-selecting mechanism to one or another of its positions; means to adjust the transmitting members to determine the position to which the counter-selecting mechanism shall be shifted, the supporting arm having a longer stroke than is necessary to shift the counter-selecting mechanism to any of its positions; and a flexible connection between the supporting arm and driving head to permit the former to complete its stroke after the arrest of the driving head.

20. In a multiple counter calculating machine, the combination with counter-selecting mechanism adapted to free one or another set of counters for operation; racks for the sets of counters; and a special key; of an actuating mechanism; a drive mechanism operable thereby; a releasable coupler to connect and disconnect the actuating and drive mechanisms; adjustable transmitting members operable by the drive mechanism to shift the counter-selecting mechanism to one or another of its positions; means to adjust the transmitting members; a control key having a flexible connection with the coupler to cause it to connect or disconnect the actuating and drive mechanisms; and means controlled by the special key to shift the coupler to, and maintain it in, idle position, when the special key is operated.

21. In a multiple counter calculating machine, the combination with counter-selecting mechanism adapted to free one or another set of counters for operation; of an actuating mechanism; a drive mechanism; a coupler mounted upon one of said mechanisms to travel therewith, and adapted to releasably engage the other of said mechanisms; a rocking bail having a loose connection with the coupler; a control key; a resilient link to connect the key and bail; transmitting members operable by the driving mechanism, to shift the counter-selecting mechanism; and means separate from the control key to rock the bail against the tension of the resilient link and disable the coupler.

22. In a multiple counter calculating machine, the combination with counter-selecting mechanism adapted to free one or another set of counters for operation; and a special key; of actuating mechanism effective at each operation of the machine; drive mechanism operable thereby; adjustable transmitting members operable by the drive mechanism, to shift the counter-selecting mechanism to one or another of its positions; means to adjust the transmitting members; a coupler to releasably connect the actuating and drive mechanisms; a control key; a flexible connection between the key and coupler, to enable the key to control the position of the coupler; and means operable by the special key to disable the coupler against the tension of the flexible connection operated by the control key.

23. In a multiple counter calculating machine, the combination with counter-selecting mechanism adapted to free one or another set of counters for operation; and a special key; of actuating mechanism effective at each operation of the machine; drive mechanism operable thereby; adjustable transmitting members operable by the drive

- mechanism, to shift the counter-selecting mechanism to one or another of its positions; means to adjust the transmitting members; a coupler to releasably connect the actuating and drive mechanisms; a control key; a flexible connection between the key and coupler, to enable the key to control the position of the coupler; and means operable by the special key to disable the coupler against the tension of the flexible connection operated by the control key, the flexible connection adapted to restore the coupler to effective position upon the return of the special key-operated means to idle positions.
24. In a multiple counter calculating machine, the combination with counter-selecting mechanism adapted to free one or another set of counters for operation; and a special key; of actuating mechanism effective at each operation of the machine; drive mechanism operable thereby; adjustable transmitting members operable by the drive mechanism, to shift the counter-selecting mechanism to one or another of its positions; means to adjust the transmitting members; a coupler to releasably connect the actuating and drive mechanisms; a control key; a rocking bail connected with the coupler; a flexible connection between the control key and bail to enable the key to control the coupler; a tripper operable by the special key; a trigger projecting from the bail and shiftable into proximity to the tripper upon the operation of the control key; to enable the special key to press the tripper against the trigger and swing the bail against the tension of the flexible connection, to disable the coupler upon the depression of the special key.
25. In a multiple counter calculating machine, the combination with a main drive shaft; manually-operable counter-selecting mechanism shiftable to one or another position, to free one or another set of counters for operation; and interlocking means controlled by the counter-selecting means, and by the main drive shaft, respectively, to prevent operation of either during an operation of the other; of mechanically-actuated means to shift the counter-selecting mechanism; a coupler to control the operation of the mechanically-actuated means; a control key for the coupler; and means operable by the control key to disable the interlocking means.
26. In a multiple counter calculating machine, the combination with a main drive shaft; manually-operable counter-selecting mechanism shiftable to one or another position, to free one or another set of counters for operation; and interlocking means controlled by the main drive shaft, and by the counter-selecting mechanism, respectively, to prevent the operation of either during the operation of the other; a starting key; and an interlock between the starting key and the counter-selecting mechanism, to prevent the operation of either during the operation of the other; of means operable by the main drive shaft to mechanically shift the counter-selecting mechanism; a control key and mechanism to render such means effective or ineffective; and a single means operable by the control key to render the several interlocking means ineffective. 75
27. In a multiple counter calculating machine, the combination with a main drive shaft; manually-operable counter-selecting mechanism shiftable to one or another position, to free one or another set of counters for operation; a locking lever; means controlled by the counter-selecting mechanism to rock the lever as the counter-selecting mechanism shifts from one to another of its positions; a dog controlled by the locking lever; a notched segment connected to the main drive shaft, and engageable by the dog to lock the main drive shaft against operation; and a normally-restrained latch adapted to coact with the locking lever to retain the counter-selecting mechanism against operation during the operation of the main drive shaft; of means, operable from the main drive shaft, to shift the counter-selecting mechanism; a control key to render such means effective or ineffective; means operable by the control key to displace the latch relatively to the locking arm, and hold the latch in such displaced position; and a disabling lever operated by the latch, to render the dog inactive. 80 85 90 95 100
28. In a multiple counter calculating machine, the combination with a main drive shaft; manually-operable counter-selecting mechanism shiftable to one or another position, to free one or another set of counters for operation; a locking lever; means controlled by the counter-selecting mechanism to rock the lever as the counter-selecting mechanism shifts from one to another of its positions; a dog controlled by the locking lever; a notched segment connected to the main drive shaft, and engageable by the dog to lock the main drive shaft against operation; a starting key; a locking arm connected with the locking lever to prevent the operation of the starting key during the operation of the counter-selecting mechanism, or vice versa; and a normally-restrained latch adapted to coact with the locking lever to retain the counter-selecting mechanism against operation during the operation of the main drive shaft; of means, operable from the main drive shaft, to shift the counter-selecting mechanism; a control key to render such means effective or ineffective; means operable by the control key to displace the latch relatively to the locking arm, and hold the latch in such displaced position; and a disabling lever operated by the latch, to render the dog inactive. 105 110 115 120 125

ing arm, and hold the latch in such displaced position; a disabling lever operated by the latch, to render the dog inactive, and means on the latch to render the locking arm inactive.

29. In a multiple counter calculating machine, the combination with a counter-selecting mechanism common to the respective sets of counters, shiftable to one or another of its positions to free one or another of the sets of counters for operation, or to restrain all sets of counters out of operation; and a shiftable paper carriage; of machine-operated drive mechanism for the counter selecting mechanism; and transmitting mechanism adjustable relatively to and operable by the drive mechanism, to shift the counter-selecting mechanism to any of its effective positions.
30. In a multiple counter calculating machine, the combination with a counter-selecting mechanism common to the respective sets of counters, shiftable to one or another of its positions to free one or another of the sets of counters for operation, or to restrain all sets of counters out of operation; and a shiftable paper carriage; of machine-operated drive mechanism for the counter selecting mechanism; transmitting mechanism adjustable relatively to and operable by the drive mechanism, to shift the counter-selecting mechanism to any of its effective positions, and means controlled by the carriage to variously adjust the transmitting mechanism.

31. In a multiple counter calculating machine, the combination with a shiftable counter-selecting mechanism common to the respective sets of counters, adapted to free one or another set of counters for operation, or to restrain all sets of counters out of operation; of automatically-operated means to shift the counter-selecting mechanism to any of its positions, including adjustable transmitting members; and means to adjust the members to render anyone or both effective, to determine the position to which the counter-selecting mechanism shall be shifted.

32. In a multiple counter calculating machine, the combination with a shiftable counter-selecting mechanism common to the respective sets of counters, adapted to free one or another set of counters for operation, or to restrain all sets of counters out of operation; of automatically-operated means to shift the counter-selecting mechanism to any of its positions, including adjustable transmitting members, shiftable to a number of positions corresponding with the several positions which the counter-selecting means may occupy; and means to variously adjust the transmitting members.

33. In a multiple counter calculating ma-

chine, the combination with a combined counter-selecting and non-add mechanism; and a shiftable paper carriage; of automatically-operable means to shift the counter-selecting mechanism to any of its positions to free one or another set of counters for operation, or to positively restrain all sets of counters out of operation.

34. In a multiple counter calculating machine, the combination with a combined counter-selecting and non-add mechanism; and a shiftable paper carriage; of automatically-operable means to shift the counter-selecting mechanism to any of its positions to free one or another set of counters for operation, or to positively restrain all sets of counters out of operation; and carriage-controlled means to adjust the means which automatically operates the counter-selecting and non-add mechanism, to determine the position to which the counter-selecting and non-add mechanism shall be shifted.

35. In a multiple counter calculating machine, the combination with a combined counter-selecting and non-add mechanism; and a shiftable paper carriage; of automatically-operable means to shift the counter-selecting mechanism to any of its positions to free one or another set of counters for operation, or to restrain all sets of counters out of operation; and a single adjusting mechanism controlled by the carriage and effective upon the means which automatically operates the counter-selecting and non-add mechanism, to determine the position to which the counter-selecting and non-add mechanism shall be shifted.

36. In a multiple counter calculating machine, the combination with a single counter-selecting and non-add mechanism; and a shiftable paper carriage; of automatically-operable means to shift the counter-selecting and non-add mechanism to any of its positions, to free one or another set of counters for operation, or to restrain all sets of counters out of operation; carriage-controlled means to determine to which of its positions the counter-selecting and non-add mechanism shall be shifted; and means to manually retain the counter-selecting and non-add mechanism in any of its positions against the influence of its automatic operating means.

37. In a multiple counter calculating machine, the combination with a single counter-selecting and non-add mechanism; and a shiftable paper carriage; of automatically-operable means to shift the counter-selecting and non-add mechanism to any of its positions, to free one or another set of counters for operation, or to restrain all sets of counters out of operation; carriage-controlled means to adjust the automatically-operable means, to determine the position to which it

shall shift the counter-selecting and non-add mechanism; and means to manually retain the counter-selecting and non-add mechanism in any of its positions against the influence of its automatic operating means.

5. 38. In a multiple counter calculating machine, the combination with a single mechanism adapted to select any set of counters for operation, or to restrain all sets of counters out of operation; of machine-actuated means to shift the counter-selecting and non-add mechanism to one or another of its positions, including a yieldable drive means; and means to retain the counter-selecting and non-add mechanism in any of its positions against the influence of the machine-actuated shifting means.

39. In a calculating machine, the combination with a plurality of sets of counters; drive members therefor; mechanism to select any set of counters to coact with its drive members, and to restrain the remaining counters in idle position; and a shiftable carriage; of drive means for the counter-selecting mechanism, actuated at each operation of the machine; transmit-

ting members adjustable relatively to and operable by the drive means, to shift the counter-selecting mechanism; and carriage-controlled means to adjust the transmitting members relatively to the drive mechanism to determine the mechanical selection of one or another of the sets of counters for coaction with its drive members.

40. In a multiple counter calculating machine, the combination with a single counter-selecting mechanism adapted to select any set of counters for operation, or to restrain all sets of counters out of operation; and a shiftable carriage; of machine-actuated means to shift the counter-selecting mechanism to one or another of its positions, including adjustable transmitting members; adjusting mechanism to variously position the transmitting members; and tappets of varying lengths mounted on the carriage and adapted to be brought into contact with the adjusting mechanism as the carriage is shifted to control the positions of the transmitting members.
